FLOOR CONSTRUCTION

Ernest Walter, Montclair, and Elmer E. Koehler,
Rutherford, N. J.

Application August 21, 1931. Serial No. 558,473

8 Claims. (Cl. 72—66)

Our invention relates to floor constructions and refers particularly to floor constructions composed of hollow fire proof blocks such as those which are made from clay or concrete.

5 The value of hollow fire proof blocks, and particularly concrete blocks, is well known and their general adoption is proof of their utility.

Among the desirable features incident to floor constructions composed of concrete, and similar, 10 hollow blocks are the adaptability of the blocks to spans and lengths of different dimensions, their ease of incorporation and construction into the finished flooring, the rigidity and stability of the produced flooring, their adaptability to form 15 a concrete unit with the poured concrete.

The hollow blocks of our invention possess all of the above, and other valuable novel features, as will be evident upon a consideration of our specification and its accompanying drawing.

20 Our invention relates to hollow building blocks adapted particularly for employment with light weight steel I-shaped beam joists and are of such construction that may be positioned between such beams and firmly locked in place by means of 25 wedges or concrete poured between them, the construction and arrangement being such that a layer of concrete thereon may be unified with concrete between the blocks and the blocks themselves thus producing a fire-proof light floor construction of great rigidity.

Our invention consists of a floor arch made of two skew blocks only instead of two skew blocks, a number of intermediate blocks and a key block incident to previously known construction. These 35 skew blocks can be made of clay, concrete, gypsum or any similar material which can be formed into precast shape. The blocks are approximately the same height as the steel joists and are usually provided with a flange on the bottom 40 which fits under the flange of the I-beam so as to protect this flange and fireproof it. The width of the two blocks and their shape where they meet in the center is such that when they are placed against the joists there is a wedge shaped space 45 left between them which may vary from zero to about 1" on the bottom. A wedge of variable thickness made of concrete, clay, gypsum, steel, wood or any other suitable material is then inserted and forced down tight. This wedge will 50 then hold the beams in position. A stiff grout is then poured into this joint and also into the space between the blocks and the joists if there are any. After this concrete is set the floor is 55 capable of carrying heavy loads.

The thickness of the wedge should be such that

the wedge after it is driven into the slot remains near the top of the blocks so as to be able to take care of the arch thrust. If the wedge would be selected that was too thin it would go too far to the bottom. Such a wedge would not have any 60 value for holding the arch. The construction of this arch system differs from the usual arch in the omission of the intermediate and the key blocks.

However, these wedges can be omitted. If the 65 blocks are erected as shown in Figure 2 where a temporary plank 43 is set up, the blocks are laid on this plank and at the same time held up on the bottom flanges of the I beams. After they are all laid a cement grout or concrete is poured 70 into the wedge space between the blocks and also between the space between the blocks and the joists. After the cement is set this makes a solid floor construction.

The disadvantages of the present employed key 75 block are that, if the steel is not set accurately on centers so as to fit the block sizes on hand, the key block may either not drop down far enough, which will make it stick out on top, or it may drop down too far which gives an unsatisfactory ceiling. In practice the steel joists are usually not spaced very accurately. The spacing varies often from a fraction of an inch to more 80 than 1".

In our system we make the two blocks small 85 enough to fit into the smallest space and by then pouring cement between the blocks it is not necessary to wedge them tight against the flanges and any varying space between the blocks is taken up by the cement which is filled into the spaces. 90

The novel and useful features of our invention are clearly set forth in the accompanying drawing with our description thereof.

In the accompanying drawing illustrating modified forms of our invention, similar parts are 95 designated by similar numerals.

Figure 1 is a perspective view of a floor construction employing one form of our hollow blocks.

Figure 2 is a perspective view of the construction 100 of Figure 1, with cement contained within the crevices between the blocks and the joists.

Figure 3 is an end view of Figure 2 with the cement flooring laid.

Figure 4 is a section through the line 4—4 of 105 Figure 3.

Figure 5 is an end view of a modified form of our floor construction.

The particular form of our floor construction shown in Figures 1 to 4 inclusive comprises the 110

two steel I beams 15 and 16, having the webs 17 and 18, and the flange ends 19, 20, 21 and 22 respectively.

5 A plurality of skew blocks are then positioned as shown. These particular skew blocks comprise a bottom 23, an angularly positioned side 24, a top 25, a curved or inclined side 26 having a recess 27 therein and a diagonal transverse strengthening wall 28, the bottom 23 extending 10 as a flange beyond the side 26 in order that the two blocks upon opposite sides of a beam will practically meet below the beam lower flange to protect its under face.

The inclined part 26 of the block is on the 15 side next to an I beam. Due to this inclined part, the block can be dropped into position from above by revolving it around the recess 27, in engagement with the lower flange of the I beam, the inclination of the side 26 being sufficient to 20 clear the top flange of the I beam. Also the outer side 24, as it swings downward, will clear the outer side of a previously positioned opposed block.

It will be noted that the web 28 in our block 25 runs diagonally from the top center between the beams to the bottom near the beams. The advantage of the inclined web 28 is that it carries the load the same as in an arch direct from the center between the beams to the lower flanges 30 of these beams, and such a block is thus much stronger.

A series of these skew blocks are positioned along the two faces of the beams, the blocks being of such width that there is a space between the 35 walls 24, 24, of opposed blocks.

Most desirably, the blocks, such as 37, 38, 39, 40, 41 and 42, are laid on a temporary plank 43, as shown in Figure 2, wedges, such as 29, 30, 31, 32 and 33, shown in Figure 1, being omitted. 40 Cement grout 35 is then poured over the whole floor area which fills all the empty spaces between the blocks and around the I beams. This grout can be made flush on top with the blocks or it can be raised above the blocks as shown at 45 36 on the left of Figure 3. After this cement grout is set the plank is removed.

It will be noted that the lower and upper flat faces of each skew block, provided respectively by its lower and upper walls 23 and 25, are parallel with one another. With opposed series of 50 these blocks in the floor, as above described and shown in the drawing, the lower faces of the bottoms 23 of all of the blocks in all of the series are in alignment in a horizontal plane; while similarly the upper faces of the tops 25 of these blocks 55 are disposed in alignment in a parallel horizontal plane and are also in alignment with the upper faces of the upper flange ends of the I-beam joists.

60 These skew blocks are firmly locked in place and to the I beams by means of the cementitious material 35 between the spaced opposed upwardly flaring inclined faces of their sides 24 and also between the inclined faces of their sides 26 and I beams. The lower portions of the side walls 26 are shown as abutting against the web faces of the I beams. The exposed flange end faces of the beams at the top, as well as also the top faces of the blocks, can be covered by means of the 65 cementitious material 36, which is shown as formed in the same mass with the cementitious material 35.

75 It will thus be seen that our construction comprises a unified mass of cement comprising the blocks and the poured cement, supported by the

steel beams and that the latter are completely covered.

There is thus formed a light hollow fire-proof floor construction.

In the modified form of blocks shown in Figure 5, the strengthening wall 28' is perpendicular.

Our invention, therefore, comprises a hollow fireproof construction adapted to beams of different lengths and of slightly different spacing, which is easy and economical of production and which is of unified concrete construction of great strength and rigidity.

We do not limit ourselves to the particular size, shape, number, arrangement and composition of parts as shown and described as these are given simply as a means for clearly describing our invention.

What we claim is:—

1. In a floor construction, in combination, a set of joists comprising spaced I beams at the same level having their webs substantially parallel with one another, two series of cementitious skew blocks having adjacent opposed side faces and having lower portions at their opposite sides supported upon the lower flanges of the respective I beams, all of these skew blocks having upper flat faces disposed in alignment with one another in an upper horizontal plane and having lower flat faces parallel with their upper flat faces and disposed in alignment with one another in a lower parallel horizontal plane, these blocks also having side faces inclined away from the web of the I beam upwardly to their upper flat faces, and a continuous filler in the space between the web of the I beam and said inclined faces and entirely covering the latter up to the level of their upper flat faces with respect to all of said blocks and I beams. 105

2. In a floor construction, in combination, a set of joists comprising spaced I beams at the same level having their webs substantially parallel with one another, two series of cementitious skew blocks having adjacent opposed side faces flaring upwardly away from one another and having lower portions at their opposite sides supported upon the lower flanges of the respective I beams, all of these skew blocks having lower flat faces extending throughout their bottoms with these lower faces disposed in alignment in a lower horizontal plane, these skew blocks having upper flat faces all disposed in alignment with one another and also in alignment with the upper faces of the upper flanges of the I beams in an upper horizontal plane parallel with the lower horizontal plane, these upper flat faces extending from the tops of said opposed flat side faces to a line in spaced relation with the edge of the top flange of the respective I beams, these blocks also having side faces inclined upwardly away from the webs of the I beams and joining their upper flat faces along said lines in spaced relation with the edges of the upper flanges of the I beams, a continuous cementitious filler filling all of the space between said upwardly flaring flat side faces, and a continuous cementitious filler 110

filling all of each of the spaces between the I beams and said side faces which incline upwardly away from the webs of the I beams. 115

3. In a floor construction, in combination, a set of joists comprising spaced I beams at the same level having their webs substantially parallel with one another, two adjacent series of cementitious skew blocks having adjacent opposed inclined flat side faces flaring upwardly in spaced relation from the bottoms to the tops thereof, the other 120

- side faces of these blocks in the lower part thereof above their bottoms each having a grooved recess therein into which is received the adjacent lower flange of an I beam for thereby supporting the skew blocks upon said I-beam flanges with the bottoms of the skew blocks extending beneath said flanges, the bottoms of the skew blocks providing throughout their extent lower flat faces all in alignment with one another in a lower horizontal plane, the tops of these skew blocks providing throughout their extent upper flat faces all in alignment with one another and with the upper faces of the upper flanges of the I beams in an upper horizontal plane parallel with the lower horizontal plane with these upper flat faces of each series of skew blocks terminating along a line spaced away from the edge of the top flange of an adjacent I beam, the side faces of these blocks adjacent to the I beams being inclined 80
- 10 upwardly away from the webs of the I beams and joining their upper flat faces along said lines in spaced relation with the edges of the upper flanges of the I beams, a continuous cementitious filler filling all of the space between said opposed 85
- 15 upwardly flaring inclined side faces, and individually continuous cementitious fillers respectively filling all of each of the spaces between the I beams and said side faces which incline upwardly away from the webs of the I beams. 90
- 20 4. In a floor construction, in combination, a set of joists comprising spaced I beams at the same level having their webs substantially parallel with one another, two adjacent series of hollow cementitious skew blocks having top and bottom 95
- 25 walls respectively providing upper and lower flat parallel faces and arranged in the floor with their upper faces all in alignment with one another and in alignment with the upper faces of the upper flanges of the I beams in an upper horizontal plane, said bottom walls providing flat 100
- 30 lower faces all in alignment with one another in a lower horizontal plane parallel with the upper horizontal plane, said skew blocks in the respective series thereof having adjacent side walls providing opposed inclined faces which flare upwardly in spaced relation with one another from said lower faces to said upper faces, a lower portion of each of the skew blocks adjacent to an I beam being supported upon the lower flange of the I beam, said skew blocks in the respective 105
- 35 series thereof having side walls adjacent the I beams providing inclined faces which diverge upwardly away from the webs of the respective I beams and join said upper flat faces along a line spaced from the edge of the upper flange of the I beam, each of said hollow skew blocks having an internal strengthening web running diagonally from side to side and from bottom to top from adjacent said lower portion supported on the lower I beam flange to substantially the junction between the opposite side wall and the top wall and in line with the upper portions of the opposed faces of these side walls, a continuous cementitious filler filling all of the space between said opposed 110
- 40 upwardly flaring inclined side faces, and individually continuous cementitious fillers respectively filling all of each of the spaces between the I beams and said inclined faces which diverge upwardly away from the webs of the I beams. 115
- 45 6. A cementitious skew block for floor construction having a flat side face inclined upwardly and inwardly of the block from the bottom to the top thereof at a sharp acute angle to the vertical, upper and lower flat faces parallel 120
- 50 with one another extending respectively from the upper and lower edges of said side face towards the other side of the block, said lower face thus extending beyond a vertical plane at which said upper face terminates, said upper 125
- 55 face thus being narrower than said lower face, another side face with its lower part even with the edge of the lower face and thence inclined upwardly and inwardly of the block to meet said narrower upper face, and a deep horizontal longitudinal groove in said lower part of the latter side face adjacently spaced above said lower face. 130
- 60 7. A hollow cementitious skew block for floor construction comprising top and bottom walls respectively providing upper and lower flat faces parallel with one another, a side wall connecting adjacent edge portions of the top and bottom walls and providing a flat face, an opposite side wall rising from the bottom wall which it connects with the top wall and provides a side face inclined upwardly and inwardly of the block and meets the adjacent edge of said upper flat face, and an internal strengthening web running diagonally from side to side and from top 135
- 65 to bottom from the connection of said flat-faced side wall with the top wall to the place at which said opposite side wall rises from the bottom wall. 140
- 70 5. In a floor construction, in combination, a set of joists comprising spaced I beams at the same level having their webs substantially parallel with one another, two adjacent series of hollow cementitious skew blocks having top and bottom 145
- 75 walls respectively providing upper and lower flat
8. A hollow cementitious skew block for floor 150

construction comprising a wider bottom wall and a narrower top wall respectively providing correspondingly wider and narrower lower and upper flat faces parallel with one another, a side wall connecting adjacent edge portions of the top and bottom walls and providing a flat face throughout its extent, an opposite side wall connecting the other edge portions of the top and bottom walls and providing a side face rising from the edge of the lower face and having a portion thereof inclining upwardly and inwardly of the block and joining the edge of said nar-
